UNITED STATES PATENT OFFICE.

ERNST CONNY EGELIN, OF STOCKHOLM, SWEDEN, ASSIGNOR TO AKTIEBOLAGET AUTOPINS, OF STOCKHOLM, SWEDEN, A CORPORATION.

BOX PARTICULARLY FOR NEEDLE-SHAPED OBJECTS.

Application filed September 7, 1923. Serial No. 661,494.

To all whom it may concern:

Be it known that I, ERNST CONNY EGELIN, subject of the King of Sweden, residing at Norra Blasieholmshamnen 5⁸, Stockholm, Sweden, have invented certain new and useful Improvements in Boxes Particularly for Needle-Shaped Objects, of which the following is a specification.

The present invention relates to a box 10 adapted particularly for needle-shaped objects, such as pins, sewing needles or the like.

Such object, as for instance pins, occur on the market, for one thing, arranged in 15 so-called papers of pins and, for the other, in disordered masses into casings. In both cases inconveniences arise as to a quick and handy seizure of the pin. The paper must be developed and the casing opened, before 20 the pin can be withdrawn, which presents in addition to the waste of time caused thereby the inconvenience that both hands must generally be used. Obviously, this involves a drawback, because the object, for instance 25 a paper, a piece of stuff or the like, into which the pin is to be put, is often held in the one hand. As to the latter case—the casing—the further inconvenience is presented that it is very troublesome to remove 30 by the fingers but one of the small pins. Generally, at the first grasp a greater or smaller number of pins is inadvertently obtained and often under very disagreeable 35 stings in the fingers. Finally, the pin must, when grasped, generally be arranged in a 40 position suitable for the use (for instance turned), so that the head of the pin will be grasped.

The present invention has for its object to 45 avoid the above-mentioned drawbacks, so as to obtain by a single and simple grasp but one pin and, besides, in a position suitable for the use.

The invention consists, chiefly, of a box 50 comprising two parts movable with relation to one another and, normally, held separated by spring-action, said parts containing partly a holder provided with seats for the objects, partly a check device 55 for the said holder and partly an abutment for the objects movable with relation to the holder, said abutment causing the objects, when moving the parts of the casing together, to successively project through an 60 opening in the box in a position suitable for

a handy grasp. The check device may, preferably, be carried out in such manner that a plurality of objects are simultaneously located within the same, and the objects may, preferably, be arranged in spiral form 60 in the holder.

In the annexed drawing two forms of embodiment of a box according to the invention and adapted for pins are shown. Fig. 1 is a cross-section of the box along the line 65 A—B of Fig. 2. Fig. 2 is a section along the line C—D of Fig. 1. Fig. 3 shows a modified driving device for the pin holder. Fig. 4 shows the said pin holder viewed 70 from above.

In the form of embodiment shown in Figs. 1 and 2, 1 designates the upper and 2 the lower part of the box. The said parts are hinged to one another at 3 and held by the spring 4 in the separated position shown. 75 Pivotally attached to the upper part 1 is by means of a screw 5 a cylinder 6 forming a journal for the sleeve-like holder 8 for the pins 9, said holder having flanges 7. Connected to a journal 10 rotatably mounted in the cylinder 6 and rigidly secured to the holder 8 is the one end of a spiral spring 11, the other end of which is secured to a pin 12 connected to the cylinder 6. The said 80 spring tends, for one thing, to rotate the holder 8 with the pins 9 in the direction of the arrow in Fig. 2, and, for the other, to turn the cylinder 6 with the holder 8 about the screw 5 in the same direction. As apparent from Fig. 2, the holes 13 for the pins 9 are in the form of embodiment shown arranged in spiral, and the outermost pin is 85 checked by a pawl 14 placed in the part 1 of the box, the check surface of said pawl being located, measured in the longitudinal direction of the pin, right beneath an opening 15 in the cover of the part 1. Secured to the lower part 2 of the box is an abutment 16, against which the point of the pin abuts, 90 when moving the parts 1 and 2 together, the pin being moved out through the opening 15 in the part 1, so as to be easily grasped at the head. Thus, if a pin be wanted, the upper part 1 of the box is simply to be 95 pressed downwards by the hand and the pin is automatically moved upwards between the fingers, and as mentioned, in a position suitable for the use. The parts 1 and 2 are then 100 by the action of the spring 4 moved apart 105 and, simultaneously, the holder 8 with the 110

pins 9 is turned by the action of the spring 11 a distance corresponding to the distance between two consecutive pins, at which time the next pin in the order is brought into contact with the pawl 14 and, thereby, in a position opposite to the opening 15.

As, in order to collect a greater number of pins in a holder having reasonable dimensions, the pins have to be arranged in several consecutive rows or, as in the form of embodiment shown, in spiral, the journal 10 of the holder 8 must be moved more and more in the direction towards the pawl, and this is effected by the cylinder 6 carrying the holder 8 being turnable, as mentioned, about the screw 5 placed eccentrically with relation to the journal 10. By locating, as apparent from Fig. 2, a plurality of pins, preferably at least three, simultaneously within the seizing surfaces of the pawl an effective guidance and a continuous action of the device is facilitated.

In the modification shown in Figs. 3 and 4, the driving device used in the form of embodiment according to Figs. 1 and 2 is substituted by a spring-actuated angular lever, pivotally connected at 17 with the pawl 14 for the pins 9. The one arm 18 of the said lever is actuated by a spring 19 secured to the pawl 14, said spring tending to bring the said arm into contact with the bottom of the part 2 of the box and holding by means of a seizing pin 21 pivotally secured to the other lever arm 20 the pins 9 into mesh with the pawl 14. The seizing pin 21 is held by means of an abutment 22 on the arm 20 in the position shown in Fig. 4, may, however, be turned freely in the opposite direction against the action of a weak spring 23. If now, as hereinbefore described, the parts of the box be moved together, a pin 9 is brought to project through the opening 15 and, simultaneously, the lever 18, 20, bearing in this position, as mentioned, on the bottom of the part 2, is turned against the action of the spring 19, and the seizing pin is moved past a number of pins, so as to, finally, when the relative movement of the parts of the box ceases, be placed behind a pin. Thus when the parts of the box be then brought apart, the pin 21 will by the aid of the lever 18, 20 and the spring 19 turn the pin holder a distance, so that the next pin in the order will be moved into contact with the pawl 14 and, thus, right before the outlet opening 15. In this case, the area 18 does not reach the bottom of the part 2 of the box, but will be held at a distance therefrom, depending on the number of pins having been passed by the pin 21, before said pin 21 is finally checked behind a pin, the already existing tension in the spring 19 being utilized for driving the pin holder, until the lever again has reached the position shown in Fig. 3.

Obviously, the device described may also

be used for other objects than pins and sewing needles or the like, if the seats in the holder only be made to correspond to the shape of the different objects. Thus, the device may, for instance, be used for paper clips of wire or the like.

What I claim as new and desire to secure by Letters Patent of the United States is:—

1. A box adapted particularly for needle-shaped objects, such as pins or the like, and for holding and projecting said objects singly into a position which adapts them to be conveniently seized, said box comprising in combination two relatively movable parts, means for forcing said parts apart, a holder for the objects within the box, said holder comprising a rotary member having seats for the objects, an abutment on one of said parts and upon the outer end of which the points of the objects will be caused to strike, means for rotatably and movably mounting the holder in said box, means for imparting rotary motion to said holder and for exerting a pressure on the holder so that it will always have a tendency to move toward said abutment, and a check device intermittently arresting said rotary holder in a position in which an object to be seized is located in front of said abutment, so that upon forcing the aforesaid movable parts of the box together the object is forced out of the holder proper and thus made easily accessible.

2. An apparatus according to claim 1, characterized by rotary holder consisting of two interconnected disks having seats for the objects.

3. An apparatus according to claim 1, characterized by the rotary holder having spirally arranged seats for the objects.

4. An apparatus according to claim 1, characterized by the rotary holder consisting of two interconnected disks having spirally arranged seats for the objects.

5. An apparatus according to claim 1, characterized by the said check device being so disposed as to co-operate directly with the objects placed in the said rotary holder.

6. An apparatus according to claim 1, characterized by the said check device being so disposed as to co-operate directly with the objects placed in the said rotary holder, and the rotary holder in addition being movable in a direction towards the check device for the objects.

7. A box adapted particularly for needle-shaped objects and the like and for holding and projecting said objects singly into a position which adapts them to be conveniently seized, comprising in combination two relatively movable parts, means for forcing said parts away from each other, a holder for the objects within the box including a rotary member having seats for the objects, means for movably mounting said holder about an axis arranged eccentrically with respect to

the axis of rotation thereof, an abutment mounted on one of said parts and upon the outer end of which the points of the objects may be caused to strike, means for imparting a rotary motion to said holder and for moving said holder in a direction towards the abutment, and a check device intermittently arresting said rotary holder in a position in which an object to be seized is located in front of said abutment so that upon forcing the movable parts together the object is forced out of the holder proper and thus made easily accessible.

8. An apparatus according to claim 7, characterized by the driving means for the holder being disposed within the holder in

such manner as to tend, for one instance, to turn the holder about its axis of rotation and, for the other, to swing the holder about the said eccentrically placed axis in a direction towards the said check device.

9. An apparatus according to claim 1, characterized by the check device being so constructed as to grasp simultaneously over a plurality of objects.

10. An apparatus according to claim 7, characterized by the check device being so constructed as to grasp simultaneously over a plurality of objects.

In testimony whereof I affix my signature.

ERNST CONNY EGELIN.
